ROCK DRILL

John C. Curtis, Garfield Heights, Ohio, assignor
to The Cleveland Rock Drill Company, Cleve-
land, Ohio, a corporation of Ohio

Application March 11, 1935, Serial No. 10,492

21 Claims. (Cl. 121—9)

This invention relates broadly to rock drills, but more particularly to feeding mechanism for rock drill of the mounted drifter type.

One object of this invention is to produce an improved feeding mechanism for rock drill of the drifter type.

Another object of this invention is to produce an improved rock drill feeding mechanism including a power actuated feeding motor and connections between the motor and the rock drill whereby the latter is fed toward or away from the work at a greater rate of speed than that of the power actuated feeding motor, this materially reducing the length of the feeding mechanism without affecting the standard feed length of the rock drill.

Another object of this invention is to produce a drill feeding and supporting mechanism including a collapsible drill guiding frame, whereby the overall length thereof may be reduced to substantially one half of the possible feed length of the drill.

Another object of this invention is to produce a feeding and supporting mechanism for use with a rock drill of the standard construction.

Other objects and advantages more or less ancillary to the foregoing and the manner in which the various objects are attained, reside in the specific construction and aggroupment of the elements peculiar to this structure, as will become apparent from a more complete examination of this specification, in the claims of which there are assembled certain specific combinations of parts and specific constructions indicative of the scope and spirit of the invention.

Referring to the drawings, in which like symbols designate corresponding parts throughout the several views;

Fig. 1 is a side elevational view of the assembly mounted on a wheel supported frame and showing the drill guiding in a collapsed position.

Fig. 2 is a portion of Fig. 1 showing the drill guiding frame in extended position.

Fig. 3 is a plan view of the assembly shown in Fig. 1.

Fig. 4 is an enlarged front elevational view of the lower end portion of the assembly shown in Fig. 2.

Fig. 5 is an enlarged longitudinal sectional view of the drill feeding and supporting mechanism embodying the present invention.

Fig. 6 is an enlarged cross sectional view taken in a plane indicated by line 6—6 in Fig. 5.

Fig. 7 is an enlarged top plan view of the upper portion of the mechanism shown in Fig. 5.

Fig. 8 is a view similar to Fig. 7 showing the lower portion of the mechanism shown in Fig. 5.

Referring to the drawings which illustrate a preferred embodiment of the invention, 10 represents a wheel supported frame having a substantially U-shaped member 11 pivotally secured thereto by means of connections 12. Affixed to the cross arm 13 of the member 11 by means of a clamp 14, there is a body or housing 15 carrying a bolt 16 protruding through the clamp 14 for receiving a nut 17 by which the housing may be locked relatively to the clamp. The housing 15 is formed with an enlarged counterbore 18 disposed at right angles with the bolt 16 and adapted to receive one end, hereinafter denoted as the rear end, of a tube 19. The other end of the tube, hereinafter denoted as the front end has disposed therein a front head or bracket 20. The housing 15 and front head 20 are secured in abutting fluid tight engagement with the end of the tube by two diametrically disposed side rods 21, each extending through the body 15 to receive a nut 22, while the front end of each rod extends through lugs 23 formed integral with the front head 20. Mounted on that extended portion of each rod, there is a tube or sleeve 24 clamped between the lug 23 and across head 25 by means of a nut 26 engaging the outer threaded front end portion of the rods. On each of the sleeves 24 is slidably mounted one half portion 27 of a drill steel centralizer which is constantly urged in engagement with the cross head 28 by the effort of a compression spring 29.

Reciprocably mounted within the tube 19, there is a piston 29 having a piston rod 30 rigidly secured thereto by a nut 31. The piston rod 30 is somewhat longer than the tube 19 and extends from one side of the piston to the exterior of the tube through the body or housing 15. To assure a fluid tight joint about the rod, the housing 15 is provided with a stuffing box 32.

Welded on the tube 19 in longitudinal alignment therewith, there are two elongated members 33 extending from near the housing 15 toward the front end thereof for a distance substantially equal to two thirds of the length of the tube. These members are formed with guideways 34 extending the full length thereof, and are adapted to slidably receive the guides 35 of a shell 36. The shell proper is formed of an arcuated body portion 37 somewhat longer than the tube 19. The upper portion of the side walls of the shell are also formed with guideways 38 having slidably mounted therein the corresponding guides 39 of a rock drill motor 40. The

guides 35 and guideways 38 extend from the front end of the shell toward the rear end thereof a distance about equal to two thirds the length of the shell. The rear end of the shell 36 is terminated by an apertured lug or connection 41 adapted to receive the screw threaded end of the piston rod 30 which is rigidly secured thereto by a nut 42. Near the lug 41, each of the side walls of the shell is formed with a longitudinal slot 43 adapted to receive a bolt-like shaft 44 transversely disposed through the shell. Carrying the shaft 44 for longitudinal movement within the slot 43, there is a U-shaped strap 45 passing over the end of the shell in straddle relation therewith. This strap is provided with an adjustment screw 46 engageable with the end wall of the shell, the purpose of which will be explained later. The shaft is locked against lateral movement by a nut 63 mounted on one end thereof and a head 47 formed integral therewith, the nut and head engaging the strap 45 as shown in Fig. 7. Toward its front end, the shell 36 has a portion of the arcuated bottom wall thereof cut away to provide an opening 48. Transversely disposed through the side walls of the shell adjacent this opening and extending therethrough, there is a shaft 49 parallel to the shaft 44. This shaft like the shaft 44 is locked against lateral movement by a head 50 and nut 51 engaging the side walls of the shell.

The upper wall of the housing 15 below the shell 36 is provided with a series of sprocket teeth 52 adapted to receive the middle portion of a chain 53 which is thereby fastened against longitudinal movement relative to the tube 19. From the housing 15, one half portion of the chain 53 extends rearwardly over a sprocket wheel 54 rotatably mounted on the shaft 44, and then forwardly to the cylinder of the drilling motor 40, where it is fastened by a chain connecting member 55 rigidly secured within the usual longitudinally apertured lug 56, depending from the cylinder. The other one half portion of the chain 53 extends forwardly from the housing 15, over a sprocket wheel 57 rotatably mounted on the shaft 49, from where it extends rearwardly to the drilling motor 40 and is connected thereto by the chain connecting member 55.

Secured to the side of the tube 19 somewhat below the housing 15, there is a valve housing 58 having a motive fluid controlling throttle valve (not shown) rotatable therein by a handle 59. The valve housing is provided with a connection 60 adapted to receive a motive fluid conveying conduit for admitting motive fluid to the valve. Since the throttle valve and its appurtenant parts form no part of the present invention, no further explanation is thought necessary other than pointing out that the motive fluid controlled by the throttle valve may be admitted in the tube 19 through a conduit 61 opening therein adjacent the housing 15, and a conduit 62 opening therein adjacent the front head 20.

The operation of the mechanism is as follows: When motive fluid is admitted from the throttle valve in the rear end portion of the tube 19 through the conduit 61, it acts on the piston 29 and housing 15. Since the latter together with the tube 19 is stationary, the piston is driven forwardly or toward the front head 20, thus causing the forward movement to the shell 36 relative to the tube 19, due to the piston rod 30 and lug 41 connecting the shell to the piston. The shell 36 carrying the sprocket wheels 54 and 57 engaging the chain 53 will cause the latter

to transmit forward motion to the drilling motor 40 at a greater rate of speed than that of either the shell or the piston. When the piston 29 is at the end of its forward stroke or about positioned as shown in Fig. 5, each end 5 of the shell extends only slightly over the corresponding end of the tube 19, and the drilling motor 40 extends only slightly over the front end of the shell 36, thus constituting an assembly of a length substantially equal to that of the tube 10 19.

When it is desired to feed the drilling motor rearwardly or away from the work, the throttle valve may be positioned for admitting motive in the front end of the tube 19 through the conduit 15 62. In this instance the motive fluid acting on the front face of the piston 29 will drive the latter, together with the shell 36, away from the work. Since the shell 36 is connected to the drilling motor 40 through the sprocket wheels 20 and the chain 53, the movement of the shell is transmitted to the motor 40 at a greater rate of speed than that of the shell 36 or piston 29. When the piston reaches the end of its rearward stroke, the rear end portion of the shell 36 carrying the drilling motor 40 extends well beyond the rear end of the shell, as shown in Fig. 5. In this instance, the front end portion of the guides 35 remaining within the guideways 34 for supporting the shell, are assisted by the piston rod 30 30 protruding from the tube 19.

The strap 45 carrying the shaft 44 on which the sprocket wheel 54 is rotatably mounted, may be moved relatively to the shell 36 for varying the tension of the chain 53, by simply rotating 35 the adjustment screw 46.

As a result of this present invention it will be noted that since the front effective area of the piston 29 is larger than the rear effective area, the power of the feeding mechanism imparting 40 feeding motion to the drilling motor away from the work is greater than that imparting feeding motion thereto toward the work. This advantageous feature has been found extremely valuable for extracting stuck drill steels from a drilled 45 hole. It will further be noted that by the slidable arrangement of the shell on the feed tube, an extremely simple and compact mechanism is obtained without affecting the standard length of feed of the drilling motor. 50

Although the foregoing description is necessarily of a detailed character, in order to completely set forth the invention, it is to be understood that the specific terminology is not intended to be restrictive or confining and it is to be further understood that various rearrangements of parts and modification of structural detail may be resorted to without departing from the scope or spirit of the invention as herein claimed. 55

I claim:

1. In a drilling apparatus, a shell having a drilling motor slidable thereon, a stationary tube having said shell slidable thereon, a power actuated piston longitudinally movable within said tube associated with said shell for imparting slid- 65 able movement thereto, and means deriving motion from the slidable movement of said shell for transmitting feeding motion to said drilling motor at a greater rate of speed than that of said shell. 70

2. In a drilling apparatus, a shell having a drilling motor slidable thereon, a feeding mechanism for said motor comprising a stationary and a power actuated longitudinally movable element, said shell being connected to the latter for move- 75

ment therewith relative to said stationary element, and means deriving motion from the movement of said shell for transmitting feeding motion to said drilling motor at a different rate of speed from that of said shell.

3. In a drilling apparatus, a stationary elongated element, a shell slidably thereon, a power actuated mechanism associated with said shell for imparting slidable movement thereto, a drilling motor slidable on said shell, and means deriving motion from the movement of said shell for transmitting feeding motion to said drilling motor at a greater rate of speed than that of said shell.

15 4. In a drilling apparatus, a slidable shell, a drilling motor slidably guided thereon, a feeding mechanism for said motor comprising a duality of elements one slidable relatively to the other, said shell being slidably guided on one of said elements and connected to the other for movement therewith, means for effecting the slidable movement of said last mentioned element and consequently of said shell, and means responsive to the slidable movement of said shell for effecting the slidable movement of said motor relative to said shell.

20 5. In a drilling apparatus, a stationary element, a power actuated mechanism within said element, a member slidably guided on said element, a drilling motor slidably guided on said member, a connection between said mechanism and member for imparting movement to the latter, and means deriving motion from the slidable movement of said member for effecting relative slidable movement between the latter and said motor.

25 6. In a drilling apparatus, a duality of elements one guided on the other for slidable movement relative thereto, a drilling motor carried by said guided element for slidable movement relative thereto, a power actuated mechanism associated with the guided element for imparting slidable movement thereto, and means deriving motion from the slidable movement of said guided element for transmitting slidable movement to said motor relative to said guided element.

30 7. In a drilling apparatus, a supporting element, a member slidably guided on said element, a drilling motor carried by said member for slidable movement relative thereto, a power actuated mechanism associated with said member for imparting slidable movement thereto and means deriving motion from the slidable movement of said member for effecting the slidable relative movement between the latter and said motor.

35 8. In a drilling apparatus, a mechanism including an elongated tubular element having an elongated member slidably guided thereon, a drilling motor slidably guided on said elongated member, power actuated means within said tubular element connected to said member for imparting slidable movement thereto, and movement transmitting connections between said member and said motor for transmitting slidable movement to the latter relative to the former.

40 9. In a drilling apparatus, a slidable shell, a drilling motor slidably guided thereon, a feeding mechanism for said motor comprising a stationary cylinder having a power actuated piston slidably therein, said shell being slidably guided on said cylinder and connected to said piston for movement therewith, and speed multiplying connections between said shell and said motor including a flexible element secured to said cylinder and said motor and rotatable members carried by

45 said shell with which said flexible member engages.

10 10. In a drilling apparatus, a slidable shell, a drilling motor guided thereon, a power actuated feeding mechanism for said motor comprising a stationary and a movable element, said shell being slidably guided on said stationary element and connected to said movable element for slidable movement therewith, and speed multiplying connections between said shell and said motor including a flexible member secured to said stationary element and said motor and rotatable members carried by said shell with which said flexible member engages.

15 11. In a drilling apparatus, a stationary elongated element, a member slidable on said element, a drilling motor slidable on said member, a power actuated mechanism associated with said member for imparting slidable movement thereto, and means associated with said element, said member and said motor for transmitting the slidable movement of said member to said motor at a rate of speed different from that of said member.

20 12. In a drilling apparatus, a stationary elongated element having an elongated member slidable thereon, a drilling motor slidable on said member, power actuated means within said element operatively connected to said member for imparting slidable movement thereto, and means for transmitting the slidable movement of said member to said motor at a rate of speed different from that of said member.

25 13. In a drilling apparatus, a slidable shell, a drilling motor slidably guided thereon, a feeding mechanism for said motor comprising a stationary cylinder having a power actuated piston slidably therein, said shell being slidably guided on said cylinder and connected to said piston for movement therewith, and a chain and sprocket 30 wheel connection between said shell and said motor whereby the slidable movement of the former is transmitted to the latter at a rate of speed different from that of said shell.

35 14. In a drilling apparatus, a stationary elongated element having an elongated member slidable thereon, a drilling motor carried by said member capable of slidable motion relative thereto, power actuated means within said element operatively associated with said member for imparting slidable movement thereto, and means actuated by virtue of the movement of said member for causing the slidable motion of said motor relative to said member.

40 15. In a drilling apparatus, a drilling motor, a feeding mechanism therefor including a shell on which said motor is slidably guided, an elongated tubular element having said shell slidably guided thereon, power actuated means within said tubular element associated with said shell for imparting feeding motion thereto, and further means between said shell and said motor for transmitting the feeding motion of the former to the latter at a rate of speed different from that of said shell.

45 16. In a drilling apparatus, a drilling motor, a feeding mechanism therefore including an elongated member having a shell slidable thereon, a movable feeding element associated with said shell for imparting feeding motion thereto, and means including a flexible draft element operatively connecting said shell to said motor for transmitting the feeding motion of the former to the latter at a rate of speed different from that of said shell.

17. In a drilling apparatus, the combination with a stationary support, of a shell slidable thereon, of a drilling motor slidable on said shell, a piston chamber within said support having a fluid actuated piston reciprocable therein and rigidly connected to the shell for imparting feeding motion thereto, and connecting means between said support and motor deriving motion from said shell for imparting feeding motion to the motor at a greater rate of speed than that of said shell.

18. In a drilling apparatus, the combination with a stationary support, of an elongated element slidable thereon, of a drilling motor slidable on said element, a feeding mechanism for said motor including a piston chamber within said support having a fluid actuated piston slidable therein and rigidly secured to said element for transmitting slidable movement thereto relative to said housing, and movement transmitting means connected to said support and motor deriving motion from the slidable movement of said element for transmitting slidable movement to said motor at a greater rate of speed than that of said element.

19. In a drilling apparatus, the combination with a stationary supporting housing, of an elongated element slidable thereon, of a drilling motor slidable on said element, a feeding mechanism for said motor including a power actuated piston slidable within said housing and rigidly connected to said element for effecting relative motion be-

tween said element and said housing, and means deriving motion from said relative motion for transmitting motion to said motor in the same direction but at a greater rate of speed than that of the relative motion aforesaid.

20. In a drilling apparatus, the combination with a stationary tube having guideways formed thereon, of an elongated member slidably guided within said guideways, of drilling motor slidably guided on said member, a feeding mechanism for said motor including a power actuated piston slidable within said tube rigidly connected to said member for imparting slidable movement thereto, and a flexible element fastened to said housing and motor and co-operating with rotatable means carried by said member for transmitting the slidable movement of said member to said motor at a greater rate of speed than that of said member.

21. In a drilling apparatus, the combination with a stationary element having a movable element slidable thereon, a drilling motor slidably guided on said movable element, a power actuated piston slidable within said stationary element rigidly connected to said movable element for imparting slidable movement thereto, and means deriving motion from said movable element for transmitting movement to said drilling motor relative to said movable element.

JOHN C. CURTIS. 30
